Patented July 13, 1976

240,530

FLUID RESERVOIR FOR PUMPS OR THE LIKE

Philip A. Kubik, 6809 Spruce Drive,
Birmingham, Mich. 48010

Filed May 8, 1975, Ser. No. 575,586

Term of patent 14 years

Int. Cl. D23—01

U.S. Cl. D23—2

Fig-1

Fig-2

Fig-3

FIG-4

FIG -5

FIG -6

FIG. 1 is a top plan view of a fluid reservoir for pumps or the like showing my new design;

FIG. 2 is a front elevational view thereof;

FIG. 3 is a bottom plan elevational view thereof;

FIG. 4 is a rear elevational view thereof;

FIG. 5 is a left-end elevational view thereof; and

FIG. 6 is a right-end elevational view thereof.

I claim:

The ornamental design for a fluid reservoir for pumps or the like, as shown.
